UNITED STATES PATENT OFFICE.

STONEWALL J. SEDINGER, OF INDIANAPOLIS, INDIANA, ASSIGNOR OF ONE-HALF TO
GROVER HANNA, OF INDIANAPOLIS, INDIANA.

PNEUMATIC RIVET-BREAKER.

1,201,986.

Specification of Letters Patent. Patented Oct. 17, 1916.

Application filed May 15, 1916. Serial No. 97,608.

To all whom it may concern:

Be it known that I, STONEWALL J. SEDINGER, a citizen of the United States, residing at Indianapolis, Marion county, and State of Indiana, have invented and discovered certain new and useful Improvements in Pneumatic Rivet-Breakers, of which the following is a specification.

My invention relates to pneumatic rivet breakers, and its object is to provide a tool of this character adapted to obtain a maximum efficiency of power from the compressed air and to enable the cost of construction of such a tool to be greatly lessened, and to enable the weight of the same to be decreased as compared with previous devices of this character, and also to provide means whereby the parts may be readily assembled.

With these objects in view, my invention is embodied in preferable form in the construction and arrangement hereinafter described and illustrated in the accompanying drawings.

In these drawings, Figure 1 is a longitudinal sectional view of the improved tool; Fig. 2, an end view of the head of the same; and Figs. 3, 4 and 5, cross sectional views on the line 3—3 of Fig. 1, illustrating the controlling valve in three positions, viz:—that given when the plunger is to be driven toward the chisel; that given it when it is to be neutral; and that given it when the plunger is to be returned toward the cylinder-head.

Referring to the drawings, 1 designates the head of the tool, which head consists of a hollow cylindrical body having a central hollow valve chamber therein, in which is adapted to be seated a cylindrical or conical rotatable air-controlling valve 2. This valve is retained in place within the chamber by means of a head plate 3 which is screwed to the head by means of screws 4. A screw bolt is attached to the valve and operates freely through the head plate and is provided at its outer end with a projecting handle 6 whereby the valve is adapted to be manually operated to alternately effect the forward driving stroke of the plunger upon the cutting chisel and the return movement of the plunger, or to seat the valve in neutral position.

In order to limit the movement of the valve and determine the registry of the ports

thereof with either the ports that establish the forward flow of the power medium or the return flow thereof, a stop pin 7 is provided in the fixed head plate, which pin enters an arcuate slot 8 formed in the outer face of the valve.

The valve is of such construction as to permit a comparatively unimpeded flow of the compressed air therethrough, thus decreasing friction and avoiding a loss of power in operating the tool. To this end, the said valve has an elongated circular port or passageway 9 extending through the wall at right angles to the axis of the valve and communicating at the center of the valve 70 with a longitudinal, elongated port or passageway 10, constituting the central bore of the valve which is adapted to communicate at its inner end with an aperture 11 leading through the inner cross wall of the valve 75 chamber head. The valve also has a cut-away segmental portion 12 constituting a flattened port which is adapted to establish communication circumferentially of the valve between two of the ports of the head 80 when turned to certain positions.

The valve head is provided with a series of four ports formed by horizontal passageways extending through the wall of the head at right angles to the axis of the valve 85 and having the centers of said ports lying in the same plane. Referring specifically to these ports, 13 is the inlet port which is adapted to have communication with a pipe 14 communicating with a hose 15 which leads to a suitable source of compressed air. 16 is an exhaust port; 17 is also an exhaust port communicating with an exhaust pipe 18, and 19 is a port adapted to communicate with the upper end of a pipe section 20, 95 which communicates by a hose 21 with the lower end of the tool in order to supply compressed air for the purpose of returning the operating plunger to normal position after each stroke. The lower end of the hose terminates in a pipe section 22 and this lower section is screw threaded into an opening formed in the side wall of a nose piece 23 which consists of a hollow shell 100 and which is provided with a surface port 24 leading from said opening and adapted to admit the compressed air to the lower end of the tool.

A hollow, longitudinal tube 25 fits between the head 1 and the shell 23 constitut-

ing the nose piece, and this tube is adapted to receive the compressed air at either end thereof. In this tube is mounted a reciprocal air-operated plunger 26 adapted to constitute the driving member for a cutting chisel 27, the shank 28 of which is freely mounted within the body of the shell of the nose piece and which chisel is adapted to be supported by the hand of one of the operators while the other operator manipulates the valve so as to direct the air current to effect the driving and return movements of the plunger. A clamping plate 29 bears against the nose piece, and the head 15 of the valve and the nose piece are held together and the tube held clamped between said parts by means of longitudinally extending bolts 30.

It will be seen that the admission port 24 leading across the inner face of the body of the nose piece 23 is below the level of said face and also beyond the end of the plunger inclosing tube 25 whereby it is unnecessary to form a port or opening through the tube 25 itself, which arrangement dispenses with the necessity of bringing two apertures into registry, when openings through both the nose piece and the tube are formed, as has heretofore been the practice, and the establishment of which registry is frequently an element of considerable difficulty in adjustment.

The operation of the tool is as follows: Assuming that it is desired to drive the plunger forward so as to force it against the chisel for a cutting operation, the valve is turned to the position indicated in Fig. 3, wherein the inlet port 13 leading from the source of compressed air will be in registry with the horizontal port 9 of the valve, whereby the power medium is directed downwardly through the opening 10 in the valve head and against the upper end of the plunger 26, forcing the latter down 45 against the end of the chisel to perform the cutting operation. In this traverse of the air, it will be seen that it is compelled to make only one angular turn, owing to the central passage and single admission port 50 through the valve. In the downward descent of the plunger, the air in the tube ahead of the same will be forced out through the ports in the nose piece into the connecting pipe 21 and thence through port 55 19 of the valve head and thence out through port 17 to the exhaust pipe 18 by means of the flattened port 12 on the periphery of the valve, which port will be brought into registry with said ports 19 and 17 whenever the valve is turned to position to admit the air for the forward stroke. To return the plunger to its upper or outer position, ready for another cutting stroke, the operator who has charge of the control of the tool turns 60 65 the valve to the position indicated in Fig.

5, whereupon the air will be admitted through the port 13 and thence by means of the flattened port on the valve through the port 19 to the connecting pipe 21 which conveys the air to the other end of the tube 70 and serves to drive the plunger toward the valve head. In this movement the air between the inner end of the plunger and the valve head is exhausted out through the opening 11 leading through the valve head 75 and through the main longitudinal passage 10 of the valve and out through the horizontal ports 9 and 16.

In Fig. 4, the valve is shown in neutral position with blank spaces thereof covering 80 the main inlet and outlet ports.

Having thus described my invention, what I claim is:

1. A pneumatic rivet breaker having an air receiving tube, a nose piece and a cylindrical head between which said tube is held, a cylindrical rotatable valve in said head having a passageway, the axis of which extends longitudinally of the axis of the tube and communicates with a port in the 90 end of the tube, said valve having also a port at right angles to the axis of the tube and meeting the longitudinal passageway of the valve and adapted to communicate with ports leading directly through the 95 head at right angles to the axis thereof, and an operating handle for the valve lying beyond the end of the head in a plane at right angles to the axis of the valve and head.

2. A portable, manually operated pneumatic rivet breaker having an air receiving tube, a reciprocable plunger therein, a cutting chisel operable by the plunger, air admitting means at both ends of the tube, a cylindrical valve head at one end of the 105 tube and in longitudinal continuation thereof, and having two exhaust ports and two air inlet ports arranged substantially in the same circle extending through the head at right angles to the axis of the tube, 110 one of said inlet ports having communication with a source of compressed air and the other having communication with the opposite end of said tube, and a controlling valve having a central longitudinal bore 115 therein having continuous communication through the valve head with said tube and having a port extending at right angles to said bore through the wall of the valve and communicating with said bore passageway, 120 said valve having also a peripheral port on its surface and being rotatably mounted in said valve head and adapted to control the flow of air against either end of said operating plunger and to control the passage 125 of the exhaust at either end of said tube, and an operating handle carried by the valve and lying beyond the end of the tool and operable in a plane at right angles to the axis of the tube.

3. A pneumatic rivet breaker having an air receiving tube, a reciprocable plunger therein, a cutting chisel operable by the plunger, a rotatable air controlling valve, a cylindrical valve head in which said valve is mounted, said valve head having an opening therethrough leading to the end of the tube and having a series of ports extending through the wall thereof at right angles to the axis of the valve, which ports have their centers in substantially the same plane, a pipe connecting one of said ports and the lower end of the tube, a source of compressed air supply, means of connection between said source and one of said ports in the valve head, two of such ports constituting exhaust ports, said valves having a central longitudinal passageway adapted to continuously register with the central opening in the valve head and having a port leading through its wall at right angles to its axis, and communicating with said central passageway and also having a peripheral port adapted to register with two of the valve
- head ports and means for determining the position of the valve to direct the air to either give the forward driving stroke to the plunger or to return the same toward the head.
4. A pneumatic rivet breaker having an air receiving tube, a cylindrical nose piece and a valve head having sockets in which the opposite ends of said tube fit and are supported, means for clamping the head and nose piece together, said nose piece having a port beyond the adjacent end of the tube leading through the socket wall and an air conveying pipe connecting a port in said valve head and said port in the nose piece.
5. In witness whereof, I have hereunto set my hand and seal at Indianapolis, Indiana, this 13th day of May, A. D. nineteen hundred and sixteen.
